UNITED STATES PATENT OFFICE

EUGENE L. REYNOLDS, OF PORTLAND, OREGON

DESIGN FOR A CASING FOR A REFRIGERATING, MIXING, AND DISPENSING MACHINE

Application filed November 17, 1930. Serial No. 37,691. Term of patent 7 years.

To all whom it may concern:

Be it known that I, EUGENE L. REYNOLDS, a citizen of the United States, residing at Portland, in the county of Multnomah and State of Oregon, have invented a new, original, and ornamental Design for a Casing for a Refrigerating, Mixing, and Dispensing Machine, of which the following is a specification, reference being had to the accompanying drawings, forming part thereof.

Fig. 1 is a perspective, front view of the article, showing my new design.

Fig. 2 is a top, plan view of the article illustrated in Fig. 1.

I claim:

The ornamental design for a casing for a refrigerating, mixing, and dispensing machine, as shown.

EUGENE L. REYNOLDS.
